UNITED STATES PATENT OFFICE.

CHARLES C. WIENTGE, OF PROVIDENCE, RHODE ISLAND, ASSIGNOR TO THE
HOWARD & SON COMPANY, OF SAME PLACE.

DESIGN FOR A SPOON.

SPECIFICATION forming part of Design No. 21,340, dated February 9, 1892.

Application filed September 30, 1891. Serial No. 407,307. Term of patent 7 years.

To all whom it may concern:

Be it known that I, CHARLES C. WIENTGE, of Providence, in the county of Providence and State of Rhode Island, have originated and produced a Design for Flat Ware such as Spoons, Forks, and Like Utensils, of which the following is a specification.

I will describe a spoon embodying the design, and then point out the novel features in

10 a claim.

In the accompanying drawings, Figure 1 is a front view of such a spoon. Fig. 2 is a back view thereof.

Similar letters of reference designate corresponding parts in both figures.

15 The bowl A of the spoon is represented as plain. Along the shank B for a considerable distance are ribs or stria b. The handle C is

embellished with a representation of a wreath or flowers. As here shown, two lines of flowers c' c² are arranged at an angle and converge toward the extremity of the handle. Where they meet a ribbon c³ is delineated. The back of the handle is embellished with a curved row of flowers c⁴.

20 25 What I claim, and desire to secure by Letters Patent, is—

The design for a spoon or analogous article, substantially as shown and described.

In testimony whereof I have signed my name to this specification in the presence of 30 two subscribing witnesses.

CHARLES C. WIENTGE.
